United States Patent Office.

N. L. SMITH, OF DERBY, CONNECTICUT.

Letters Patent No. 89,949, dated May 11, 1869.

IMPROVEMENT IN ALARM FEED-WATER REGULATORS FOR BOILERS.

The Schedule referred to in these Letters Patent and making part of the same.

To all whom it may concern:

Be it known that I, N. L. SMITH, of Derby, in the county of New Haven, and State of Connecticut, have invented a new and improved Water-Regulator and Alarm-Attachment to Steam-Boilers; and I do hereby declare that the following is a full, clear, and exact description thereof, which will enable those skilled in the art to make and use the same, reference being had to the accompanying drawings, forming part of this specification, in which—

Figure 1 represents a side elevation, partly in section, of my improved regulator.

Figure 2 is a plan or top view of the same.

Figure 3 is a side elevation of a modification of the same.

Similar letters of reference indicate corresponding parts.

This invention relates to a new apparatus for regulating the height of water in a steam-generator, or for sounding an alarm in case there is too little or too much water in the boiler.

The invention consists in the arrangement of the vessel, which is, by jointed or flexible pipes, connected with the boiler, but not arranged within the same, and which, when it is filled with water, overcomes the power of a spring or weighted lever, and descends, operating, by that motion, either a valve to the pump, or whistle, or a lever for throwing the pumping-engine out of gear, while it will be raised to set the pump or alarm in motion when too little water should be in it.

A, in the drawing, represents a frame, of suitable size and form, in which a hollow vessel, B, of suitable size, is held.

This vessel rests only on a spring, C, or on a weighted lever, whereby it is held raised, if too light.

By means of two jointed or flexible pipes, D and E, the vessel B is connected with the steam-boiler F, so

that the water shall be at equal height in both these vessels, B and F.

When the water in the boiler should rise above a certain line, the weight of water in the vessel will overcome the power of the weighted lever or spring C, and the vessel B will descend.

By this motion it will operate a valve, a, in a pipe, G, by means of a rod, b, and crank c, as shown, or by other suitable mechanism, and will thereby either close the feed-pipe, to prevent further water from entering the boiler, or cause the blowing of a whistle, or both, so that the further rise of water in the boiler is either automatically stopped, or notice is given to stop it.

As soon as the water sinks in the boiler, the vessel B will get lighter, and will be raised by the spring or weighted lever, so as to open the valve a, to let in more water, or to sound an alarm.

Instead of the aforesaid apparatus and valve, the vessel B may, as in fig. 3, act on a bell-crank, H, which is, by a rod, I, connected with the rod J, which serves to connect the pump-piston with the walking-beam K.

As soon as the vessel B descends, it will cause the crank H to swing, whereby the rod J is swung off its connection with the beam, as indicated in fig. 3. The rising of the vessel will automatically re-establish that connection.

I claim as new, and desire to secure by Letters Patent—

The arrangement of the yielding vessel B, stand A, and jointed pipes D E, with reference to the boiler F and whistle G, when constructed substantially as herein set forth.

N. L. SMITH.
